BRAKE MECHANISM FOR AUTOMOTIVE VEHICLES.

Application filed September 8, 1927, Serial No. 218,119, and in Canada August 8, 1928.

Our invention consists in the novel features hereinafter described, reference being had to the accompanying drawings which illustrate one embodiment of the same, selected by us for purposes of illustration, and the said invention is fully disclosed in the following description and claims.

In the operation of vacuum brakes for automotive vehicles or other vacuum or suction actuated devices in connection with internal combustion engines, it is convenient to obtain the necessary suction from a suction passage of the internal combustion engine located between the throttle valve and the cylinders of the engine, as for example, the intake manifold of the engine. It is found, however, that the air exhausted from the suction actuated mechanism and delivered into the intake manifold or suction passage of the engine, tends to interfere with the operation of the engine on which the suction for the operation of the suction actuated device depends, or to stall the engine and put an end to the suction, and thus interfere also with the operation of the suction actuated device. It has also been found that the withdrawal of air from the suction actuated device during the application of the brake mechanism for the purpose of preventing interference with the operation of the engine, tends to retard the operation of the brake mechanism to a greater or less extent, and is therefore undesirable. The withdrawal of considerable quantities of air from a suction actuated device into the manifold of the engine, is also likely to materially delay the starting of the engine. It is also to be understood that in the operation of vacuum brake mechanism, the piston or other moving part of the suction actuated device is acted upon by differential pressures brought about by producing a condition of rarefaction on one side of the piston and admitting air on the other side, under the control of suitable reversing valve mechanism, and that the air so admitted is thereafter necessarily withdrawn and delivered into the suction passage of the engine.

The object of our invention is to provide means in connection with a multi-cylinder internal combustion engine and a suction actuated device or devices operatively connected therewith, whereby a quick and efficient operation of the suction actuated de-

vice may be obtained, while the air withdrawn from the suction actuated device and delivered into a suction passage of the engine is prevented from stalling the engine if idling, or materially interfering with the operation thereof, and with the operation of the suction actuated device, which depends upon the engine for its suction, and which consists in providing the engine with a plurality of independent carburetors, each of which is connected with a separate manifold section for independently supplying charges of explosive mixture to certain cylinders only of the engine, and to provide in connection therewith, a suction actuated device comprising a cylinder and piston, which may be connected with brake mechanism of the vehicle, for example, the operation of the cylinder on one side of the piston being connected at all times to one of said separate intake manifold sections by a suitable tubular connection, and the portion of the cylinder on the other side of the piston being connected by a suitable tubular connection with another of said intake manifold sections under the control of suitable valve mechanism which may be, for example, an ordinary two-way valve by means of which the portion of the cylinder on one side of the piston may be disconnected from its manifold section and connected with the atmosphere to produce a power stroke of the piston in a direction to apply the brake mechanism. The valve mechanism may be turned into a position to disconnect the said portion of the cylinder both from the atmosphere and from the manifold section with which it is connected, to maintain the brakes applied, and may also be operated to re-connect it with said manifold section, to withdraw the air admitted to operate the brake mechanism and equalize pressures on opposite faces of the piston, to effect an immediate release of the brake mechanism and permit it to return with the piston to retracted position, under the influence of the retracting springs with which the brake mechanism is provided. With this arrangement the air will be withdrawn from the actuator cylinder forward of the piston and delivered into one manifold section when the piston is in retracted position, and while it may somewhat interfere with the operation of the cylinders connected with such manifold section, it would

100

105

have no effect whatever on the operation of other cylinders of the engine supplied by a different manifold section not connected in any way with the suction actuated device, 5 and very little air would be withdrawn from the cylinder in rear of the piston into the manifold section connected therewith, so that the engine could be readily started and would be operated by the firing of the 10 charges in cylinders not affected materially by the withdrawal of air from the suction actuated device, and the cylinder of the latter would be exhausted on both sides of the piston, leaving the piston, as we term it, 15 submerged in vacuum, so that a very quick operation of the brake mechanism can be effected, by simply admitting air to the cylinder in rear of the piston, without admitting any appreciable quantity of air to the 20 manifold section connected with the cylinder forward of the piston so that the engine would continue to operate during the application of the brake mechanism and the release of the brake mechanism can be effected 25 without materially interfering with the cylinders receiving their charges from the other manifold sections not connected with the cylinder of the suction actuated device in rear of the piston. As the air is not simultaneously withdrawn from the suction actuated device from both ends of the cylinder at the same time, our invention is applicable to a 30 four cylinder engine, for example, having two carburetors and two separate manifolds, 35 each supplying two cylinders of the engine only. We preferably, however, desire to employ in carrying out our invention, an engine provided with more than two manifold sections, as for example, in the case of a six 40 cylinder engine, we prefer to employ three carburetors and three separate manifold sections, each supplying explosive charges to two cylinders, as in such case there will be at all times certain cylinders not connected 45 with either end of the cylinder of the suction actuated device. Our invention, may, however, be carried into effect in connection with a six cylinder engine for example, having two carburetors and two separate manifold sections, each supplying explosive 50 charges to three cylinders. In like manner, our invention may be carried out in connection with engines having 8, 12, 16, or more cylinders, in which separate carburetors and separate manifolds or manifold sections supply 55 different groups of cylinders.

In the accompanying drawings,

Fig. 1 is a diagrammatic view showing an installation in an automotive vehicle comprising an internal combustion engine of the multi-cylinder type, brake mechanism for the vehicle, and vacuum or suction actuated power actuators for the brake mechanism and having our present invention embodied 60 therein.

Fig. 2 is a detail sectional view of one form of valve mechanism which may be employed in carrying out our invention, showing it in the off position.

Fig. 3 is a similar view showing the valve 70 in position to effect the power stroke of the piston.

Fig. 4 is a similar view showing the valve 75 in an intermediate position, for holding the brakes as applied.

In Fig. 1, 60 represents an internal combustion engine for propelling the vehicle, in this instance provided with six cylinders and having a plurality of intake manifold sections, each supplying a separate group of cylinders, and each manifold section being provided with a separate carburetor. In this instance we have shown the engine provided with three intake manifolds, 61, 62, 63, each of which is connected with two cylinders of the engine for supplying the explosive charges thereto. It will be understood that the engine might be provided with a single manifold divided into three separate sections, each communicating with its own carburetor and supplying charges to a group of cylinders, and the result would be exactly the same as hereinafter described. Each of the manifold sections shown is provided with a separate carburetor, the carburetors being indicated at 64, 65 and 66. Each of the separate suction passages or intake manifold sections is provided with a separate throttle valve, the throttle valves being indicated at 67, 68 and 69 respectively, and the throttle valves may be operatively connected for joint operation from suitable control mechanism, as indicated in Fig. 1.

1 represents the cylinder of a suction or vacuum operated power actuator, adapted to be supported by the chassis of the vehicle. In this instance the cylinder is shown closed at both ends by heads, 2, 2, and provided with a piston, 3, and piston rods, 5 and 6, extending through opposite cylinder heads. 110 One of the piston rods, as the piston rod, 5, is operatively connected with brake mechanism for the vehicle in any usual or desired manner. The brake mechanism may be of any preferred type and may be applied to as many wheels as desired. In the present instance we have represented the brake mechanism of the vehicle diagrammatically in Fig. 1, as comprising a brake drum, 70, brake band, 71, brake applying lever, 72, provided with a retracting spring, 73, and connected by a link, 74, with the piston rod, 5, for purposes of illustration. In this instance we have shown a suction pipe, 26, connected with the cylinder forward of the piston therein and connected with one of the separate suction passages of the engine, between the throttle valve therefor and the group of cylinders supplied thereby, the pipe, 26, being in this instance connected to 115 120 125 130

the manifold section, 62. 27 represents another suction pipe connected to the rear end of the cylinder, 1, in rear of the piston, and connected to another separate suction passage in the same manner, in this instance to the manifold section, 63. The suction pipe, 27, is provided with suitable valve mechanism, which may be an ordinary two-way valve, indicated at 28, and illustrated in detail in Figs. 2, 3 and 4, for purposes of illustration. In this instance the valve comprises the valve casing, 28^a, provided with oppositely disposed suction ports, indicated at 29 and 30, and to which are connected portions of the suction pipe, 27, the portion of said pipe between the valve and the manifold, 63, being given the reference numeral, 27^a. The valve casing is also provided with air inlet port, 34, communicating with the atmosphere. 31 represents the rotary valve plug provided with the passage, 32, extending diametrically through the plug and normally connecting the two portions, 27 and 27^a, of the suction pipe in which the valve mechanism is located, the said plug being provided with a branch passage, 33, communicating with the central passage, 32, and adapted to connect the section, 27, of the suction pipe, leading from the valve mechanism to the cylinder in rear of the piston with the atmospheric port, 34, when the valve is turned into the position indicated in Fig. 3, for example, at which time the section, 27^a, of the suction pipe, leading from the valve mechanism to the intake manifold section, 63, will be closed. The valve plug is conveniently provided with a suitable handle, 40, for operating the same. The suction pipe, 26, is preferably provided with a check valve, 35, and the portion, 27^a, of the suction pipe, leading from the valve mechanism to the manifold section, 63, is preferably provided with a check valve, 36, said check valves serving to normally maintain in the portions of the cylinder operatively connected therewith, the highest degree of rarefaction produced in the suction passage or manifold section with which each is connected, between operations of the actuator, and also to prevent any of the explosive mixture or motor fuel from passing into the cylinder of the actuator.

The valve mechanism controlling the actuator is normally in the position shown in Fig. 2, so that each suction pipe connects one end of the actuator cylinder with one of the intake manifold sections. The piston will normally be in retracted position in close proximity to one end of the cylinder, in which position it is held by the retracting springs for the brake mechanism, indicated at 73, which also holds the brake mechanism in released position. In starting the engine, the air will be exhausted from the cylinder forward of the piston through the suction

pipe, 26, and delivered into the manifold section, 62, and the small quantity of air in rear of the piston will be withdrawn through the suction pipe, 27, and discharged into the separate manifold section, 63. The withdrawal of the considerable quantity of air forward of the piston may temporarily interfere with the operation of the cylinders supplied by the manifold section, 62, but the engine will start readily, as a comparatively small quantity of air will be discharged into the manifold section, 63, and where certain of the cylinders are supplied by manifold section not connected with either end of the cylinder, as shown, for example, in Fig. 1, the cylinders supplied by that manifold section will not be affected at all. The starting of the engine will, therefore, not be delayed by the exhaustion of air from the power actuator. When the engine is running under normal conditions, and the actuator is not being operated, all the cylinders of the engine will receive their full charges of explosive mixture without diminution or dilution and the air having been exhausted from the cylinder on both sides of the piston, the piston of the actuator is submerged in vacuum. To effect an operation of the actuator and an application of the brake mechanism, it is only necessary for the operator to rotate the plug, 31, of the valve, by means of the handle or lever, 40, substantially a quarter turn, thus cutting off the rear end of the cylinder from its source of suction, to wit, the manifold section, 63, as indicated in Fig. 3, and connecting the air inlet or atmospheric port, 34, with the port, 29, thus connecting the cylinder in rear of the piston with the atmosphere. Air at once rushes into the cylinder in rear of the piston, building up pressure, and causing the piston to move in the direction of the arrow, Fig. 1, to apply the brake mechanism. As the portion of the cylinder forward of the piston is maintained in an exhausted condition, the actual operation of the brake mechanism will not discharge any material quantity of air into the intake manifold section, 62, with which it is connected, and the operation of the engine will not be affected, and there is no possibility of stalling the engine by the operation of the actuator to apply the brake mechanism, as will be readily seen. Even if some air was withdrawn from the cylinder forward of the piston, and delivered to the manifold section, 62, the engine cylinders connected with the manifold section, 63, and in this instance those connected with the manifold section, 61, will not be affected, as no air would be delivered to either of said manifold sections from the actuator and the engine would continue to operate under any circumstances.

When the brakes have been applied to the

desired extent, the plug valve may be shifted to an intermediate position, as indicated in Fig. 4, in which the portion of the cylinder in rear of the piston is cut off, both from the source of suction and from the atmosphere, thus retaining the pressure accumulated in rear of the piston and holding the brakes as applied. By a further shift of the valve plug, 31, to its normal position, indicated in Fig. 2, the cylinder in rear of the piston will be again connected with its source of suction, and the air admitted to apply the brakes will be withdrawn, immediately releasing the brakes and permitting them and the piston of the actuator to be returned to normal position by the retracting spring, or springs, for the brake mechanism; indicated at 73. During the release of the brake mechanism and its return to normal position, air will be discharged into the intake manifold section, 63, but no air will be discharged into the intake manifold section, 62, and of course none will be discharged at any time into the manifold section, 61, if more than two manifold sections are provided. In any case, the discharge of air into the manifold section connected with the cylinder in rear of the piston during the return movement of the brake mechanism and piston will not materially interfere with the operation of the engine, which will continue to operate as usual with the cylinders not connected with the manifold, 63.

It will be seen that in carrying our invention into effect, no restricting action is applied to the suction pipes or passages, and by normally maintaining the piston submerged in vacuum a quick application of the brake mechanism is effected, by simply connecting the cylinder in rear of the piston with the atmosphere and no retardation of the action of the piston, which might otherwise be caused by the fact that the actuator depends for the suction forward of the piston on the pumping action of a group of engine cylinders and piston less than the whole number, is avoided. If there is any retardation of the action of the piston due to this cause, it will affect only the return movement of the piston when the brakes are released and return to normal position. This does not interfere with the highest efficiency of the brake mechanism, as the application of the brake mechanism will be extremely rapid and the withdrawal of even a small quantity of air from the cylinder in rear of the piston will permit the immediate release of the brakes from their frictional contact.

It will be understood that in the operation of our invention, should sufficient air be admitted to the intake manifold section connected with either end of the cylinder, so as to interfere with the firing of the charges in the cylinders connected with that manifold section, the engine would continue to

operate with the cylinders connected with the other, or other, manifold sections, and as soon as the reverse movement of the piston occurs, the cylinders affected would resume firing even though the cylinders connected with another manifold section might be affected sufficiently to cause them to cease firing, but the engine would continue to operate under the action of the cylinders fired by either one or other of said manifold sections, even though there were no other manifold sections not connected with either end of the actuator cylinder, as is the case with the manifold section, 61, herein shown. It will also be seen that as each of the independent suction passages or manifold sections acts as a storage reservoir, by connecting the cylinder of the actuator, as in the manner herein shown and described, the air is withdrawn from one end of the actuator cylinder into one of said reservoirs and from the other end of the cylinder into the other of said reservoirs, thus increasing the suction capacity available for the actuator. It will be apparent that the valve, 28 may control any desired number of power actuators, by providing the necessary pipe connections. By way of illustration we have shown a second actuator in Fig. 1 which may be located on the same vehicle, or a separate vehicle as a trailer, and connected with other brake mechanism. This actuator comprises the cylinder, 101, and piston, 103, having its piston rod, 105, connected with other brake mechanism, the parts of which are indicated in the same manner as that previously described, and given the same numerals with 100 added. The pipe, 27, is provided with a branch pipe, 127, connected with the cylinder, 101, in rear of the piston and the suction pipe, 26, is provided with a branch pipe, 126, connected with the cylinder, 101, forward of the piston. These pipes are shown provided with cut off valves, 127^a and 126^a, respectively, so that these pipes may be disconnected if desired, as where the cylinder, 101, is located on a trailer and it is desired to use the main vehicle without the trailer. We have also shown the pipes, 27 and 26, provided with additional branches, 227 and 226, equipped with cut off valves, 227^a and 226^a, as indicating that any desired number of power actuators can be connected in the manner previously described and operated by a single valve mechanism.

Our invention also facilitates starting the engine, especially where more than one actuator is employed. When starting the engine the pistons of the actuators will be in retracted position against one end plate of their respective cylinders, and most of the air contained in the cylinders will be on the forward side of the pistons. This air will be withdrawn into one of the manifolds, 130

and while it may delay the starting of the cylinders connected therewith, it will not affect the starting of the cylinders connected with the other manifold or manifolds, and as only a very small amount of air is to be withdrawn from the actuator in rear of the piston, which passes to another manifold this can be readily accomplished without materially delaying the starting of the cylinders connected with this manifold.

It will also be understood that although the pistons are maintained normally submerged in vacuum, it is not a theoretical vacuum, but is a partial vacuum or rarification, averaging from 18 to 20 inches of mercury. Therefore a rapid application of the brakes, especially where a plurality of actuators are employed would admit sufficient air to affect the engine charges in the manifold with which the forward portions of the actuator cylinders are connected, (by pipes, 26, 126; etc.), and it is also obvious that where a plurality of actuators are used, a far greater quantity of air must be withdrawn from the actuator cylinders in rear of their pistons which would materially affect the engine charges in the manifold with which the said portions of the actuator cylinders are connected, (by pipes, 27, 127, etc.) but by our invention this can be accomplished without stalling the engine, if idling, or materially delaying the starting of the engine.

What we claim and desire to secure by Letters Patent is:—

1. The combination with a multi-cylinder internal combustion engine provided with a plurality of separate suction passages each supplying explosive charges to certain only of the engine cylinders, a carburetor communicating with each of said suction passage, and a throttle valve for each of said passages, of a suction actuated device comprising a cylinder closed at both ends and a piston in said cylinder, a tubular connection extending from the cylinder on one side of the piston to certain of said suction passages less than the whole number thereof, a tubular connection from said cylinder on the other side of the piston therein to certain other of said suction passages less than the whole number thereof, and controlling valve mechanism for the suction actuated device, whereby the air withdrawn from said suction actuated device in the operation thereof is prevented from being discharged into the charges for all of the engine cylinders, to avoid stalling the engine, if idling.

2. The combination with a multi-cylinder internal combustion engine, provided with a plurality of intake manifold sections, each supplying explosive charges to separate cylinder, or cylinders, of the engine, a separate carburetor for each of said manifolds, a throttle valve interposed between each car-

buretor and its manifold, of a suction actuated device comprising a cylinder closed at both ends, and a piston in said cylinder, a tubular connection extending from the said cylinder forward of the piston to certain of said manifold sections less than the whole number thereof, and connected thereto between the throttle valve, or valves, thereof, and the engine cylinders, a tubular connection from said actuator cylinder in rear of the piston to certain other of said remaining manifold sections less than the whole number thereof, and connected thereto between the throttle valve, or valves thereof and the engine cylinders, and controlling valve mechanism for the suction actuated device, certain of said manifold sections being unconnected with the suction actuated device, whereby the withdrawal of air from the suction actuated device will not materially affect the operation of the engine or stall it if idling.

3. The combination with a multi-cylinder internal combustion engine provided with a plurality of intake manifolds, each connected with certain cylinders only of the engine, a separate carburetor for each cylinder, and a throttle valve interposed between each carburetor and its manifold, of a suction actuated device comprising a cylinder closed at both ends, a piston in said cylinder, a tubular connection from said cylinder on one side of the piston to one only of said manifolds between the throttle valve and the engine cylinder or cylinders supplied thereby, a tubular connection from said cylinder of the suction actuated device on the opposite side of the piston with another of said manifolds between the throttle valve and the engine cylinder or cylinders supplied thereby, and controlling valve mechanism for the suction actuated device, whereby the air withdrawn from the operation of the suction actuated device will be alternately delivered into said manifolds to prevent the engine from stalling if idling.

4. The combination with a multi-cylinder internal combustion engine provided with a plurality of independent suction passages, each connected with certain only of the engine cylinders, a separate carburetor for each of said passages, and a throttle valve for each of the same, of a power actuator comprising a cylinder closed at both ends, a piston in said cylinder, a tubular connection from said cylinder on one side of the piston therein to one of said suction passages between the throttle valve and the engine cylinder or cylinders supplied thereby, a connection from said cylinder on the other side of the piston therein to another of said suction passages between the throttle valve and the engine cylinder or cylinders supplied thereby, said engine having certain of said suction passages unconnected with said ac-

tuator cylinder, and controlling valve mechanism for the power actuator, whereby the operation of the power actuator is prevented from materially interfering with the operation of the engine and from stalling it if idling.

5. In an automotive vehicle, the combination with a multi-cylinder internal combustion engine for propelling the same, said engine being provided with a plurality of separate passages, each of which supplies explosive charges to certain only of the engine cylinders, a separate carburetor connected with each of said suction passages, a throttle valve in each of said suction passages between the carburetor and the engine cylinder or cylinders supplied thereby, of a power actuator including a cylinder closed at both ends, a piston in said cylinder operatively connected with brake mechanism for the vehicle, retracting means for said brake mechanism and piston, a tubular connection from said actuator cylinder forward of the piston to certain of said suction passages of the engine less than the whole number between the throttle valve thereof and the engine cylinder or cylinders supplied thereby, a tubular connection from said actuator cylinder in rear of the piston and certain other of said suction passages between the throttle valve therefor and the engine cylinder or cylinders supplied thereby, whereby said actuator piston is normally maintained submerged in vacuum, and means for disconnecting the actuator cylinder in rear of the piston from its source of suction and admitting atmospheric air to apply the brake mechanism without admitting material quantities of air into the suction passage connected with the actuator cylinder forward of the piston and for re-connecting the actuator cylinder in rear of its piston with its source of suction to withdraw the air previously admitted and permit the release of the brake and the return of the brake mechanism and piston to retracted position without admitting air to the other suction passage connected with the cylinder, whereby material interference with the operation of the engine, or stalling it if idling, by the operation of the power actuator is prevented.

6. In an automotive vehicle, the combination with a multi-cylinder internal combustion engine for propelling the same, provided with a plurality of suction passages, each of which supplies explosive charges to certain only of the engine cylinders, a separate carburetor for each of said suction passages, a throttle valve in each of said suction passages between the carburetor and the engine cylinder or cylinders supplied thereby, of a power actuator including a cylinder closed at both ends, a piston in said cylinder operatively connected with

brake mechanism of the vehicle, yielding retracting means for said brake mechanism and piston, a tubular connection from the actuator cylinder forward of its piston to one of said suction passages between the throttle valve and the engine cylinder or cylinders supplied thereby, a tubular connection from the actuator cylinder in rear of the piston to another of said suction passages between the throttle valve therefor and the engine cylinder or cylinders supplied thereby, and controlling valve mechanism in said last mentioned tubular connection, normally maintaining the actuator cylinder in rear of the piston in communication with the suction passage with which it is connected, to normally maintain the actuator piston submerged in vacuum, and provided with means for disconnecting the said portion of the actuator cylinder from said suction passage and connecting it with the atmosphere to effect a power stroke of the actuator piston to apply the brakes without discharging appreciable quantities of air into the suction passage connected with the actuator cylinder forward of the piston, said valve mechanism being movable into a position to close off the portion of the actuator cylinder in rear of the piston from its source of suction and from the atmosphere to maintain the brakes as applied, said valve mechanism being movable into a position to re-connect said portion of the actuator cylinder with its source of suction to withdraw the air previously admitted and permit the brakes to release themselves without discharging the air into the suction passages not connected with said portion of the actuator cylinder, whereby the engine will be prevented from stalling if idling.

7. In brake mechanism for automotive vehicles, the combination with a multi-cylinder internal combustion engine provided with a plurality of suction passages, each supplying explosive charges to certain only of the engine cylinders, a separate carburetor for each of said suction passage, a throttle valve in each of said suction passages between the carburetor and the cylinder or cylinders supplied thereby, of a plurality of power actuators each comprising a cylinder closed at both ends, and a piston in said cylinder operatively connected with brake mechanism, yielding retracting means for said brake mechanisms and pistons, tubular connections from one of said suction passages, between the throttle valve and the engine cylinder or cylinders supplied thereby, to each of the actuator cylinders forward of its piston, tubular connections from another of said suction passages between the throttle valve therefor and the engine cylinder or cylinders supplied thereby and each of said actuator

cylinders in rear of its piston, and controlling valve mechanism for said last mentioned tubular connections for controlling all of said actuators simultaneously constructed to normally maintain the actuator cylinders in rear of their pistons in communication with the suction passage with which they are connected and the actuator pistons submerged in vacuum, and to disconnect said portions of the actuator cylinders from said suction passage and connect them with the atmosphere to effect power strokes of the actuator pistons to apply the brake mechanisms without discharging appreciable quantities of air into the suction passage connected with the actuator cylinders forward of their piston, and to reestablish communication between the portions of the actuator cylinders in rear of their pistons with the suction passage connected therewith to withdraw the air previously admitted and permit the brake mechanisms to release themselves without discharging the air not connected with said portions of the actuator cylinders, whereby the engine will be prevented from stalling if idling.

8. In brake mechanism for automotive vehicles, the combination with a multi-cylinder internal combustion engine provided with a plurality of intake manifold sections each supplying explosive charges to separate cylinder or cylinders of the engine, a separate carburetor for each of said manifolds, a throttle valve interposed between each carburetor and its manifold section, of a power actuator comprising a cylinder closed at both ends, and a piston in said cylinder operatively connected with brake mechanism of the vehicle, retracting means for said brake mechanism and piston normally maintaining the piston adjacent to one end of the cylinder, a tubular connection extending from the cylinder forward of the piston to certain of said manifold sections less than the whole number thereof, and connected thereto between the throttle valve or valves thereof and the engine cylinders, a tubular connection from said cylinder in rear of the piston to certain other of said remaining manifold sections, and controlling valve mechanism in said last mentioned tubular connection, normally maintaining the actuator cylinder in rear of the piston in communication with the manifold section or sections with which it is connected and constructed to disconnect it therefrom and place it in communication with the atmosphere, whereby when the motor is started with the brakes released the small amount of air in rear of the actu-

ator piston will be readily withdrawn and the engine cylinders connected with certain of the manifolds will be readily started, although the engine cylinders connected with the manifold to which the actuator cylinder forward of the piston is connected may be delayed in starting by reason of the large amount of air to be withdrawn from the said portion of the actuator cylinder. 70

9. In brake mechanism for automotive vehicles, the combination with a multi-cylinder internal combustion engine, provided with a plurality of suction passages, each of which supplies explosive charges to certain only of the engine cylinders, a separate carburetor for each suction passage, a throttle valve in each suction passage between the carburetor and the engine cylinder or cylinders supplied thereby, of a plurality of power actuators each comprising a cylinder closed at both ends and a piston in said cylinder operatively connected with the brake mechanism, yielding retracting means for said brake mechanisms 85 and piston, normally holding each piston adjacent to the rear end of its cylinder, tubular connections for connecting one of said suction passages between its throttle valve and the engine cylinder or cylinders supplied thereby with each actuator cylinder forward of its piston, tubular connections from another of said passages between the throttle valve therefor and the engine cylinder or cylinders supplied thereby and each actuator cylinder in rear of the piston therein, and controlling valve mechanism for said last mentioned tubular connections normally maintaining the actuator cylinders in rear of their pistons in 100 communication with the suction passage to which they are connected, and the actuator pistons submerged in vacuum, and provided with means for disconnecting said portions of the actuator cylinders from said suction passage and connecting them with the atmosphere to apply the brakes, whereby when the engine is started with the brakes released the small amount of air to the rear of the pistons will be readily withdrawn and the engine cylinders connected with certain suction passages will be readily started, although the suction passage connected with the actuator cylinders forward of their pistons may be delayed in 110 starting by the large amount of air to be withdrawn from said portions of said cylinders. 115

In testimony whereof we affix our signatures.
